UNITED STATES PATENT OFFICE.

ERNEST H. RUEDIGER, OF BISMARCK, NORTH DAKOTA.

CONSTANT-TEMPERATURE BATH.

1,323,105.

Specification of Letters Patent. Patented Nov. 25, 1919.

Application filed March 4, 1919. Serial No. 280,645.

To all whom it may concern:

Be it known that I, ERNEST H. RUEDIGER, a citizen of the United States, residing at Bismarck, in the county of Burleigh and 5 State of North Dakota, have invented certain new and useful Improvements in Constant-Temperature Baths, of which the following is a specification.

This invention relates to liquid baths and 10 has for its principal object the production of a device which will maintain a uniform temperature of liquid within the bath.

Another object of this invention is the production of a constant temperature liquid 15 bath and wherein liquid of a desired temperature is maintained within a tub, while means are provided for forcing liquid from a contiguous receptacle into the tub for keeping the liquid within the tub at a de- 20 sired temperature.

Another object of this invention is the production of a system wherein a thermostatic circuit closer is employed for starting the motor when the temperature of the 25 liquid bath changes thus causing a pump to be actuated by the motor for forcing liquid from a receptacle into the bath for maintaining a predetermined temperature for the liquid within the bath.

One practical form of construction and 30 assembly of the present invention will be hereinafter described and is illustrated in the drawing, in which:—

The figure is a longitudinal sectional view 35 through the device, portions of the construction being shown in elevation.

In the preferred embodiment of the present invention about to be described, 5 designates a box, which may be of any desired 40 size or shape, in which the mechanism is carried whereby the entire device may be easily lifted and carried to a desired place and will be protected from injury and will only require a minimum amount of space.

Although the box may be made of any desired material, if made of wood it is preferably provided with the lining 6 of metal for preventing leakage, it is obvious that if the box is made of wood or like material 50 and then a sheet metal lining is provided the box will be made much lighter than if made of metal entirely.

A tub 7 is placed within the box and may be of any desired shape, although of course 55 it should preferably conform to the contour of the interior of the box. The receptacle

8 is likewise carried within the box and at a slight distance from the tub 7 and spaced from the walls of the box, as shown at 9 thus providing sufficient space for liquid 60 overflowing the receptacle to pass from the box through the waste pipe 10.

A pump casing 11 for a conventional form of centrifugal pump is carried within the receptacle 8 adjacent the upper portion 65 thereof and has a delivery pipe 12 leading downwardly therefrom toward the bottom of the receptacle. The conduit 13 is connected to the delivery pipe 12, this conduit 13 extending from the receptacle 8 and 70 spanning the space between the receptacle 8 and the tub 7 and passing into the tub as shown. A return conduit 14 communicates with the lower portion of the tub 7 and also with the lower portion of the receptacle 8. 75

In order to illustrate a complete structure, a suitable form of circuit closure 15 is carried within the tub 7 and has conductors 16 connected thereto, the conductors also being connected to the motor 17. The shaft 18 80 is connected to the motor and likewise to a suitable pump within the casing 11 not being deemed necessary to be herein illustrated as any form of pump may be employed. 85

When the device is in use, the receptacle 8 may be filled with any suitable liquid, such as water and obviously the water will also pass from the receptacle through the conduit 14 into the tub 8, thus causing the 90 liquid level within the tub and the receptacle to be the same. The receptacle is filled until it runs over the same and this waste liquid passes from the box through the waste pipe 10. As it is the object of this 95 invention to have a cold liquid bath, ice may be placed in the receptacle 8 to chill the liquid therein.

As above pointed out, since it is the object of the invention to provide a constant temperature cold liquid bath, the thermostatic circuit closer is set to close the circuit when the temperature of the liquid within the receptacle rises above a predetermined degree. Thus a circuit will be closed over the conductor 16 and the motor will operate to drive the shaft 18 and actuate the pump within the casing 11. As the pump is driven it will force liquid from the receptacle through the delivery pipe 12 and thence 110 through the delivery conduit 13 into the tub 8 it being noted that the liquid thus

forced from the receptacle is from a point adjacent the ice therein, thus causing the liquid to be very cold. As the chilled liquid is thus forced into the tub, the temperature of the liquid within the tub 7 will be lowered until it reaches a predetermined low degree and at this time the circuit closer will be acted upon to break the circuit over the conductor 16 thus causing the motor 17 to stop. This action will cause the pump to cease operating, whereupon further forcing of the liquid into the tub will stop. As the chilled liquid above referred to passes into the tub, some of the liquid originally carried within the tub will pass through the conduit 14 back into the receptacle 8 wherein it again will be chilled.

Thus it will be seen that the liquid within the tub 7 will be maintained at a desired temperature and accordingly articles or material to be cooled will be placed within the tub. It is therefore apparent that the device is particularly advantageous in medical diagnosis, especially for certain forms of reaction and tests.

The foregoing description and accompanying drawings have reference to what might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent is:—

1. In a device of the class described, the combination of a tub, a receptacle carried adjacent said tub, a delivery conduit connecting said receptacle to said tub, a return conduit communicating with the receptacle, and the tub, and means for forcing liquid from said receptacle through said delivery conduit into said tub, while some liquid from said tub will flow therefrom through the return conduit into said receptacle, thus retaining the liquid within the tub at a desired temperature.

2. In a device of the class described, the combination of a tub, a receptacle carried adjacent said tub, a pump casing carried adjacent the upper portions of the receptacle and having a delivery pipe depending therefrom, a horizontally extending delivery conduit leading from said pipe and extending to communicate with the interior of said tub, a return conduit carried below the delivery conduit and communicating with said tub and receptacle, a thermostatic circuit closer carried within said tub, a motor carried within said receptacle, the circuit embodying the circuit closer and motor, a motor shaft extending from said motor, pump means carried within said pump casing and being connected to said shaft, whereby when the circuit is closed the motor will operate for driving the shaft and operating the pump thus causing liquid in said receptacle to be forced through the said delivery pipe and supply conduit into said tub, while liquid from the tub will pass through said return conduit into the receptacle thus keeping the liquid within the tub at a desired temperature.

3. In a device of the class described, the combination of a box, a waste pipe leading from said box, an enlarged tub carried within said box, a reduced receptacle carried within said box, a delivery conduit connecting said receptacle to said tub, a return conduit communicating with said tub and receptacle, and means for forcing liquid through said delivery conduit from said receptacle to said tub to maintain the liquid within the tub at a desired temperature although liquid within the tub may pass through said return conduit into said receptacle, and waste liquid from said receptacle will overflow the same and pass from said box through said waste pipe.

In testimony whereof I affix my signature in presence of two witnesses.

ERNEST H. RUEDIGER.
